[57] CLAIM

The ornamental design for a telephone network interface apparatus, as shown and described.

DESCRIPTION

FIG. 1 is a front elevational view of a telephone network interface apparatus showing our new design in closed position;

FIGS. 2 and 3 are respectively right and left side elevational view thereof;

FIG. 4 is a rear elevational view thereof;

FIGS. 5 and 6 are respectively bottom and top plan views thereof;

FIG. 7 is a front and top and right side perspective view thereof, with the subscriber cover padlocked;

FIG. 8 is a front and right side perspective view thereof with the subscriber cover in opened position; and

FIG. 9 is a front and right side perspective view thereof with the padlocked subscriber cover in opened position when the padlocked cover is overridden by telephone company personnel.

FIG. 1

FIG. 2

FIG. 3
